UNITED STATES PATENT OFFICE.

LLOYD M. WILLIAMS, PERCY J. WILLIAMS, AND CHESTER L. WILLIAMS, OF SAN FRANCISCO, CALIFORNIA; EMMA F. WILLIAMS, ADMINISTRATRIX OF THE SAID CHESTER L. WILLIAMS, DECEASED, ASSIGNORS TO WILLIAMS BROS. AIRCRAFT CORPORATION, OF SAN FRANCISCO, CALIFORNIA, A CORPORATION OF CALIFORNIA.

ACCELERATOR.

Application filed August 18, 1921. Serial No. 493,248.

To all whom it may concern:

Be it known that we, LLOYD M. WILLIAMS, PERCY J. WILLIAMS, and CHESTER L. WILLIAMS, residing at San Francisco, in the county of San Francisco and State of California, have invented new and useful Improvements in Accelerators, of which the following is a specification.

This invention relates to improvements in internal combustion engine accelerators of the type used in connection with motor cars and which provide for control of the fuel.

One of the objects of the invention is to provide accelerator mechanism of the character described which may be readily and easily incorporated with the standard or factory equipped throttle controlling mechanism of certain makes of motor cars without necessitating any material changes in the construction and arrangement of said standard mechanism or requiring employment of skilled labor.

Another object of the invention is to provide accelerator mechanism which will permit of independent operation of the hand and foot operated means so that when the hand operated means is operated the operation of the foot mechanism will not be effected and vice versa.

The invention further resides in the particular combination, inter-relation and relative arrangement of certain specially and novelly constructed elements or parts of the mechanism, which elements provide for a general improvement in accelerator mechanism by way of simplification of structural arrangement and reduction of the number of parts employed, by way of increased compactness and decreased cost of production and provision of an easier and more reliable and certain attachment and operation of the mechanism.

The invention possesses other advantages and features some of which, with the foregoing will be set forth at length in the following description where we shall outline in full that form of the invention which we have selected for illustration in the drawings accompanying and forming a part of the present specification. In said drawings we have shown one form of the construction of our invention, but it is to be understood that we do not limit ourselves to such form

since the invention as expressed in the claims may be embodied in a plurality of forms.

Referring to the drawings:

Fig. 1 is a broken plan view of a portion of an automobile showing the mechanism of this invention attached thereto.

Fig. 2 is a fragmentary sectional view taken thru the foot boards and showing partly in section and in elevation the foot operating means or pedal.

Fig. 3 is an enlarged top plan view of one of the specially constructed elements of the mechanism of this invention.

Fig. 4 is a cross sectional view taken on line 4—4 of Fig. 3.

Fig. 5 is a top plan view of one of the adjusting members of the invention.

Fig. 6 is a vertical sectional view of the member shown in Fig. 5.

Fig. 7 is a broken top plan view similar to Fig. 1, showing a modified form of guide for the flexible wire.

Fig. 8 is an enlarged side elevation of the foot or pedal operated mechanism showing it partly in section and

Fig. 9 is a fragmentary sectional view showing the socketed end of the pedal.

Referring to the drawings:

1 designates a foot board of an automobile of a well known make, thru which foot board the usual steering mechanism 2 extends and upon which steering mechanism a standard hand throttle controlling means 3 is mounted. The means 3 comprises a rotatable rod 4, an operating handle 5 working in conjunction with a notched quadrant 6 of the steering wheel 7. A crank arm 8 is attached to the lower end of the rod 4 and is disposed beneath the floor boards. The carburetor 9 is provided with the customary throttle valve crank arm 10.

In attaching the mechanism of this invention to a motor vehicle of the type shown in the accompanying drawings, the usual link or connecting rod, not shown, which serves as a means of connection between the crank arm 10 and crank arm 8 is removed and in place thereof a rod 11, is used. The rod 11 is provided with a right angularly bent end 12 which is pivotally secured as at 13 to the outer end of the crank arm 8, the other end of the rod 11 extends to a point

adjacent to the throttle valve crank arm 10 but is preferably, not directly connected therewith. As a means of resilient connection, between the rod 11 and crank arm 10 we employ a sleeve 14 longitudinally slideable or movable upon the rod 11. The sleeve 14 carries an apertured ear 15 in the aperture of which a pin 16 is fixedly mounted. This pin is pivotally secured by means of the usual elements 17 to the outer end of the throttle valve crank arm 10. The sleeve 14 is held extended and in engagement with an adjustable stop member 18 on the outer end of the rod 11, by a helical expansion spring 19 which surrounds the rod 11 and at its ends abuts one end of the sleeve 18 and a collar or stop member 20 surrounding and fixed to the rod 11 at a point spaced from the outer end of said rod. This spring normally holds the sleeve so extended that the throttle valve will be closed.

To regulate the extent of the outward movement of the sleeve the stop member 18 has an angularly faced head 22 at one end and is provided with internal screw threads 23 within said head. These screw threads co-operate with the screw threaded end 24 of the rod 11. The body of the member 18 is oppositely slotted from one end as at 24 and as a means for locking the member in adjusted position a cotter pin 25 is inserted thru an opening provided in the rod and lies within the slots 24. By removing the cotter pin the member may be turned upon the rod to cause it to move longitudinally. The carburetor is provided with the usual adjusting mechanism 26 which cooperates with the adjustable stop member 18 in adjusting the mechanism.

The foot operated mechanism comprises pedal means consisting of a base plate 27 held by fastening elements 28 upon the foot board 1. A pedal 29 is pivoted intermediate of its ends as at 30 on the foot board 27 and is provided with an opening 31 in its outer end. Thru one side of the opening a slot 32 is cut and corresponding to this an opening and a slot 33 and 34, respectively are provided in the adjacent end of the base plate 27. Preferably a slotted socket member 35 extends from the under side of the plate 27 in registration with the opening 34. A flexible wire 36 is connected at one end to the pedal 29 and likewise connected at its other end to the sleeve 14. A substantially semi-circular member 37 is fixed to the upper end of wire 36 and engages in a similar shaped seat 38 therefor, in the upper side of the opening in the pedal. This structure provides for easy movement of the head in the opening or seat therefor, so as to relieve strains on the wire 36. By having slots in the pedal, plate and socket, the wire and the member 37 may be quick-

ly and easily fitted into and removed from connection with the pedal.

The other end of the wire is clamped upon the top of an extension 40 carried by the sleeve 14. The extension 40 is provided with an opening 41 thru which a headed screw or bolt 42 is inserted. Nuts 43 are turned upon the screw threaded end of the bolt so as to bring the head of the bolt into position to clamp the wire 36 upon the extension 40, as shown in Figs. 3 and 4. The extension 40 is provided on opposite sides with flanges 44 between which the head of the bolt lies in such position that the head is held against turning by said flanges. These flanges are notched as at 45 and the wire engages in the notches, as shown in Figs. 3 and 4. By this construction the end of the wire may be securely adjustably connected to the sleeve, the securing or adjusting or detaching being easily and quickly effected.

As a means for guiding and holding the wire so as to provide for an easy pulling thereof when the pedal is depressed, we employ means which will produce a curve or arc at a point intermediate of its ends. Since the line of pull from the pedal is approximately at right angles to the line or direction of movement of the sleeve it is necessary to provide this curve in the wire near a point where the same extends outwardly from the rod so that the rod may be pulled freely. As shown in Fig. 1 we employ a curved tube 46, one end of which extends into and is held upon a tubular member 47, which latter is fixed to the collar 20. The collar 20 and tubular member 47 may be integral or otherwise constructed. The wire 36 is extended thru the tubular member 47 and thru the tube 46. The tube 46 is preferably rigid and of such a curve that free and easy pulling of the wire may be effected when the pedal is depressed.

We do not wish to limit ourselves to the use of the curved rigid tube as a means for guiding and providing for a free and easy pulling of the wire. We have found that it is necessary to provide some means between the ends of the wire as a bearing and guiding means against or around which the wire may be pulled without undue friction and while we have shown a curved rigid tube for accomplishing this, we wish it understood that we may employ any other means which will provide for this purpose.

Operation.

When the hand operating mechanism 3 is actuated in the usual manner to open the carburetor, the crank arm 8 communicates a pull to the rod 11 causing the same to move bodily whereupon, thru the medium of the sleeve 14 and pin 16, the crank arm 10 will

be moved so as to open the throttle valve. During this movement, due to the flexibility of the wire 36, no movement is transmitted to the pedal 29 nor is the sleeve 14 moved 5 relative to the rod 11.

When the foot pedal 29 is depressed a pull is communicated to the wire 36 and the sleeve 14 is moved inwardly upon the rod 11 against the action of the spring 19. When 10 said sleeve 14 moves inwardly the crank arm 10 moves to open the throttle valve. This movement takes place without effecting any movement of the rod 11 or in any way moving the hand operating mechanism. Upon 15 release of the pedal 29, the spring 19 expands and moves the sleeve 14 to normal position and closes the throttle valve. Thus it will be seen that operation of either mechanism is independently carried out.

20 Referring particularly to Figs. 7 and 8, wherein there is illustrated a modified form of the invention, the construction is the same as in the form hereinbefore described, except as regards the guarding and guiding 25 means for the flexible wire 50. In this form the wire 50 is connected with the sleeve 14 at one end and with the pedal 29 at its other end and instead of having a curved rigid tube 46, we employ a flexible tube 30 51. Preferably this tube is secured at its ends to the tubular member 47 and socket member 35 of the base plate 27. The upper end of the flexible tube 51 engages in the socket 35 so that said upper end is held 35 against moving when a pull is communicated to the wire 50. Thus the tube is maintained in curved form and serves as an effective guide and bearing to permit of free pulling of the wire and at the same time said tube 40 will flex when the rod 11 moves bodily. Thus operation of either the hand or foot mechanism will not effect operation of the other mechanism.

By the term swivel connection we wish it 45 understood that we have in mind connections other than those wherein a movement of the parts is a rotary as well as a swinging movement and we consider a pivot connection or a hinge connection to be equivalent to the swivel connection referred to 50 herein, particularly inasmuch as in either and all connections the movement of the wire is limited in its passage through the slots in pedal and pedal pieces regardless of 55 the character of the swinging or swivel connection.

We claim:

1. In an accelerator, the combination with 60 the hand operated crank arm and the throttle valve crank arm of the throttle valve controlling mechanism of an internal combustion engine, of a rod connected with the hand operated crank arm, a member relatively movable upon the rod and operatively

connected with the throttle valve crank 65 arm, a spring normally holding said member extended, a foot operated means and a flexible element connected with said relatively movable member and said foot operated means, said foot operated means comprising 70 a plate, a pedal mounted upon said plate, said pedal having a socket adjacent to one of its ends and provided with a slot opening into said socket, said element adapted to enter said socket thru the slot and a member on the element engaging in said socket, said plate having an end opening slot for reception of the element and a depending slotted socket member registering 75 with the slot and socket in said pedal. 80

2. In an accelerator, the combination with the hand operated crank arm and the throttle valve crank arm of the throttle valve controlling mechanism of an internal combustion engine, of a rod connected with the hand operated crank arm, a member relatively movable upon the rod and operatively connected with the throttle valve crank arm, a spring normally holding said member extended, a foot operated means and a flexible 85 element connected with said relatively movable member and said foot operated means, said foot operated means comprising a plate, a pedal mounted upon said plate, said pedal having a socket adjacent to one of its ends and provided with a slot opening into said socket, said element adapted to enter said socket thru the slot and a member on the element engaging in said socket, said plate having an end opening slot for reception of the element and a depending slotted socket member registering 90 with the slot and socket in said pedal, one end of said guide member 95 engaging in said depending socket member. 100

3. In an accelerator, the combination with the hand operated crank arm and the throttle valve crank arm of the throttle valve controlling mechanism of an internal combustion engine, of a rod connected with the hand operated crank arm, a member relatively movable upon the rod and operatively connected with the throttle valve crank arm, a spring normally holding said member extended, a foot operated means, a flexible element connected with said relatively movable member and said foot operated means, a projection on the relatively movable member with which said element engages, spaced flanges on said projection having slots therein receiving said element, a bolt inserted 115 thru said projection with its head engaging between said flanges and clamping the element to said projection and a nut holding said bolt in place. 120

4. In an accelerator, the combination with the hand operated crank arm and the throttle valve crank arm of the throttle valve controlling mechanism of an internal com- 125

- internal combustion engine, of a rod connected with the hand operated crank arm, a member relatively movable upon the rod and operatively connected with the throttle valve crank arm, 5 a spring normally holding said member extended, a foot operated means, a flexible element connected with said relatively movable member and said foot operated means, a slotted tubular member having internal 10 screw threads mounted upon said rod and with which said relatively movable member engages, said rod having screw threads cooperating with the screw threads of said tubular member and means for holding the 15 said tubular member in adjusted position arranged to engage in the slots of said member.
5. In an accelerator the combination with the hand operated crank arm and the throttle valve crank arm of the throttle valve controlling mechanism of an internal combustion engine, of means of connection between said crank arms including a rod, a member movable relative to the rod and connected with one of said crank arms, a member adjustable on said rod and serving 20 as a stop for said movable member, a pedal, means of operative connection between the pedal and the movable member, said adjustable member having a slot therein and 25 a fastening element carried on the rod and engaging in the slot to hold said adjustable member in adjusted position.

arm, a foot operated mechanism including a flexible element, said movable member having a slot therein in which the flexible element is mounted and a headed fastening member secured to said movable member, 30 with its head clamping the flexible element.

6. In an accelerator the combination with the hand operated crank arm and the throttle valve crank arm of the throttle valve controlling mechanism of an internal combustion engine, of means of connection between said crank arms including a rod, a member movable relative to the rod and connected with one of said crank arms, a member adjustable on said rod and serving 35 as a stop for said movable member, a pedal, means of operative connection between the pedal and the movable member, said adjustable member having a slot therein and 40 a fastening element carried on the rod and engaging in the slot to hold said adjustable member in adjusted position.
